COMBINATION GARMENT

Joseph H. Le Coney, Bedford, Mass., assignor to
Shepherd Worsted Mills, Newton, Mass., a trust
of Massachusetts

Application December 19, 1936, Serial No. 116,748

2 Claims. (Cl. 2--92)

This invention relates to combination garments and more particularly to the combination of a coat sweater and a front panel or shield.

The principal object of the invention is the provision of a panel or shield adapted to cover and to be fastened to the front of the body for affording protection to that portion of the body when a coat sweater is worn unbuttoned and opened in the front.

10 Another object is the provision of means for fastening the panel to the front of the body which will not cause the panel to stretch transversely when made of knitted material, and, thereby, detract from its appearance.

15 Other objects of the invention will be set forth hereinafter.

My invention contemplates the provision of a panel or shield for covering the front portion of the body, and adapted to be fastened to the body, 20 and to be worn underneath and in conjunction with a coat sweater for permitting the sweater to be worn unbuttoned and open in front when desired. When the sweater is so worn, the panel affords full protection to the front of the body, 25 and when made of the same material as the sweater, it enhances the attractive appearance of the costume.

In the accompanying drawing illustrating one embodiment of my invention, Figure 1 is a 30 front view of a person wearing a garment made in accordance therewith, comprising a coat sweater in opened position and a panel fastened to the front of the body and partially exposed by the open sweater;

35 Fig. 2 is a front view of the panel;

Fig. 3 is a rear view of the panel; and

Fig. 4 is a front view of the upper portion of the panel with a modified form of collar.

Referring to the drawing, 18 designates a coat 40 sweater of ordinary and well-known construction, and 12 a panel or shield. The sweater is preferably provided with sleeves 14 and the front flaps are finished with edge bands 16, one carrying buttons 18 and the button-holes 20 for buttoning the 45 two flaps together down the front. The panel or shield 12 approximates a rectangular form of a length slightly less than the length of the sweater with which it is to be worn and of a width sufficient to cover the front portion of the body. The 50 upper end is formed with its two side edges 22 converging in an upward direction to the neck line 24, where it is provided with a neck band 26, the two ends of which are provided with fastening means such as complementary snap fasteners 28 55 and 30 for securing the band around the neck to

support the panel in proper position on the front of the body.

In Figure 4, there is shown a modified form of neck band 24, which, when the panel is made of knitted material, may be knitted integral therewith in one piece. In such case, the natural elasticity of the knitted material permits the neck band to stretch sufficiently to be pulled over the head when the panel is arranged on the body of the wearer.

10 For fastening the panel to the body, it is provided at approximately the waist line with a transverse band 32 of tape or other suitable non-stretchable material, the ends of which are sufficiently long to go around the body and to be 15 tied together at the back to hold the panel close to the front of the body. Preferably, the band 32 is secured to the inner face of the panel by lines of edge stitching 34 and this is done while the panel is in normal unstretched condition. This prevents stretching of the panel when it is fastened to the body by tying the ends of the band 32 at the back, which stretching detracts from the appearance of the panel.

20 Preferably, the coat sweater and panel are made 25 of knitted or loosely woven material of matched color and pattern, but, if desired, they may be different from each other in one or both of these respects. The coat sweater may vary in style and may button partially or entirely up the front. 30

In use, the panel is first arranged on the front of the body with the neck band around the neck of the wearer and is fastened thereto by tying together the ends of the band at the waist. The coat sweater is then put on. If the sweater buttons only part way up the front of the body, as many styles do, the panel serves as a neck piece, but when the sweater is left unbuttoned, it serves as a panel to fill in the space between the front flaps with the same color and texture as the 40 sweater and thereby enhances the neatness and attractiveness of the wearer's appearance.

45 It is to be understood that my invention is not to be limited to the exact form herein shown and described, since it may be embodied in other forms within the purview of the following claims.

What I claim is:

1. A one-piece panel or shield of knitted material adapted to be worn with and under a coat sweater of similar material for covering the front 50 of the body of the wearer and having a neck band for supporting it in proper position on the body and having a non-stretchable tape band stitched to its inner face transversely thereof at approximately the waist line, said tape having extensible 55

ends adapted to be tied together at the back of the body for holding said panel in unstretched position on the front of the body.

5 2. A one-piece knitted panel or shield adapted to be worn with and under a coat sweater of similar material for covering the front of the body of the wearer, said panel or shield being approximately the same length as said sweater and having an endless neck band for supporting it in

proper position, said neck band being knitted integral with said panel permitting it to be drawn over the head, and a non-stretchable tape band stitched to the inner face of the panel transversely thereof at approximately the waist line, said band having extensible ends adapted to be tied together at the back of the body for fastening said panel thereto.

JOSEPH H. LE CONEY.
